DESIGN FOR A MOLD FOR FOOD PATTIES

John H. Osgood and Wallace A. Goodwin,
Sierra Madre, Calif.

Application April 9, 1946, Serial No. 129,707

Term of patent 14 years

(Cl. D44—1)

To all whom it may concern:

Be it known that we, John H. Osgood and Wallace A. Goodwin, both citizens of the United States, residing at Sierra Madre, in the county of Los Angeles and State of California, have invented a new, original, and ornamental Design for a Mold for Food Patties, of which the following is a specification, reference being had to the accompanying drawing, forming part thereof.

Fig. 1 is a perspective view of a mold for food patties, in open position, showing our new design;

Fig. 2 is a top plan view of such food mold in open position;

Fig. 3 is a side elevational view of such food mold in open position;

Fig. 4 is a bottom plan view of such food mold in open position;

Fig. 5 is an end view of such food mold in open position taken as indicated by the arrow 5 of Fig. 3; and

Fig. 6 is an end view of such food mold in open position taken as indicated by the arrow 6 of Fig. 3.

We claim:

The ornamental design for a mold for food patties, as shown.

JOHN H. OSGOOD.
WALLACE A. GOODWIN.
